UNITED STATES PATENT OFFICE.

ARTURO DURÁN, OF SAN ANTONIO, TEXAS, ASSIGNOR OF ONE-HALF TO JAMES M. DWYER, OF SAN ANTONIO, TEXAS.

SEMAPHORE SIGNAL.

Application filed September 25, 1923. Serial No. 664,763.

To all whom it may concern:

Be it known that I, ARTURO DURÁN, a citizen of Mexico, residing at San Antonio, in the county of Bexar and State of Texas, have invented certain new and useful Improvements in Semaphore Signals, of which the following is a specification.

This invention relates to signals, and has special reference to semaphore signals of the 10 type used to control traffic on street corners and other similar places.

More particularly the invention relates to improvements in the signalling semaphores such as are illustrated in the patents previously granted to me, and bearing the Numbers 1,406,625 and 1,434,050. In these patents, there is disclosed a semaphore standard located at a street intersection, and carrying at its top a signal device operable by the passage of vehicles over certain platforms located at the street corners. The semaphore used is of the common "stop-stop, go-go" type, and normally sets in the neutral position, being turned by the passage of an automobile, say in a westerly direction, to cause the stop-stop blades to face north and south, and stop the north bound traffic. In the 20 patents above referred to, no provision was made for retarding the return of the signal to neutral position, but just as soon as the car leaves the platform, the signal swings back to neutral. This of course is apt to cause confusion and produce a collision.

One important object of the present invention is to provide an improved semaphore arrangement of the type disclosed in the aforesaid patents and to have, in this improved arrangement, means for retarding the return of the signal to neutral position.

A second important object of the invention is to provide an improved semaphore signal having an adjustable control for the retarding means.

A third important object of the invention is to provide, in a signal as above described, means for instantly releasing the platform mechanism upon the signal being set.

A fourth important object of the invention is to provide, in a device as described, an improved mechanism whereby the signal will require more time for resetting when moved to permit the passage of traffic in one direction than will be required by the resetting when removed to permit the passage of traffic in a direction at right angles thereto.

It is to be noted that this is an important feature since it is seldom that traffic on intersecting streets is uniform.

With the above and other objects in view as will be hereinafter apparent, the invention consists in general of certain novel details of construction and combinations of parts hereinafter more fully described, illustrated in the accompanying drawing and specifically claimed.

In the accompanying drawing like characters of reference indicate like parts in the several views; and:

Fig. 1 is a general elevation of the improved device.

Fig. 2 is a view showing the interior mechanism at the lower part, the casing being shown in section.

Fig. 3 is a section on the line 3—3 of Fig. 2.

Fig. 4 is an enlarged detail section on the line 4—4 of Fig. 2.

Fig. 5 is a detail view of the dial used in setting the retarding device.

Fig. 6 is a detail section through a certain lock mechanism in its normal or unlocked position.

Fig. 7 is a view similar to Fig. 6 showing the parts in locked position.

Fig. 8 is a detail view showing the parts used to set the retarding device in one position.

Fig. 9 is a view similar to Fig. 8 with the parts in a second position.

Fig. 10 is a detail section on the line 10—10 of Fig. 9.

Figure 11, is a sectional view taken along the line 11 of Figure 6.

Figure 12 is a section view taken along the line 12—12 of Figure 7.

Figure 13 is a top plan view of a portion of the retarding device.

Figure 14 is an enlarged view of a latch reversing device and its operating means.

Figure 15 is an enlarged view taken along the line 15—15 of Figure 10 and showing the latch in an operative position.

Figure 16 is a view similar to Figure 15, showing the latch in a releasing position.

Figure 17, is a view of a street crossing equipped with this signal.

In the present embodiment of the invention, there is provided a casing 10, having a hollow base 11 and extending upwardly from this casing is a tubular standard 12

carrying on its upper end a signal head 13 having the usual semaphore blades 14 and lamp 15. These semaphore blades and lamps are carried on a hollow shaft 16 which 5 is provided with a foot step or thrust bearing 17 at its lower head, located in a hollow boss 18 formed centrally of the bottom of the base 11. Just above this boss there is fixed on the shaft 16 a collar 19 having 10 projecting arms 20 to which are pivotally connected the pull chains 21 which pass out of the base, being guided by suitable idler pulleys 22. These chains go to the platforms 22' as described in my prior patents. 15 Moreover, the usual springs 23, such as are also described in such patents are employed to maintain the arms 20 in such position that the signal is normally neutral, that is to say, with its blades 14 diagonally across 20 the street intersection. Within the casing 10 is supported a spider or ring 24, depending from which are pairs of guide standards 25. Between each pair of guide standards slides a lug 26 formed on a counterweight 25 27 which is normally urged downward by means of a coil spring 28 bearing on the counterweight, and on the underside of the spider 24. Centrally of the spider or ring 24 is a tubular boss 29 and centrally of the 30 counterweight is a tubular member 30 having a rack 31 carried on one side in a suitable slot 32. This rack 31 is arranged to mesh, upon elevation of the counterweight, with a gear 33 which in turn meshes with 35 a pinion 34, fixed on a shaft 35 carrying a crank 36. In the upper part of the casing 10 is mounted a cylinder 37 which is open at its bottom end and in which moves a piston 38 connected to the crank 36 by a 40 piston rod 39. The pinion 34 is secured on the shaft 35 to rotate therewith in one direction by means of a ratchet clutch 40 of the usual spring pressed type. Thus, when the weight 27 is elevated, the parts are so arranged that the pinion 34 may rotate freely 45 without moving the piston 38. In the upper end of the cylinder 38 is an angular air passage 41 controlled by a needle valve 42. This needle valve carries at its upper 50 end a beveled gear 43, which meshes with a beveled gear 44 carried on a setting stem 45, having a key receiving aperture 46 in its upper end, and carrying a pointer 47 which traverses a dial 48 divided to indicate 55 minutes and fractions thereof.

In the operation of this part of the apparatus it will be noted that upon elevation of the weight 27, no movement of the piston takes place but, as the weight 27 descends the piston moves in its cylinder, and the rate of this movement is controlled by the opening or closing of the needle valve, the setting of this valve being in turn controlled by the position of the hand or pointer 47. Thus, it is possible to set the

time required for the piston to drop from raised position to its lowermost position, at any desired quantity by simply adjusting the needle valve.

Within the base 11 is fixed a spider 49, and above this spider on the shaft 16 is fixed a disk 50 having lock notches 51 formed in its periphery, these notches being in opposed pairs, the disk thus forming a ratchet movable with the signal. At the lower ends of the guide bars 25 are slides 52 carrying pins 53, which are connected to pins 54 on the collar 50 by springs 55. The slides 52 are slotted as at 56, and in these slots are anchor portions 57, each pivoted on a pivot pin 58, and provided with arms 59 for engaging in the notches 51. These anchor portions thus form pawls and have their outer ends formed as hollow cams 60, and each of these cams receives a pin 61 extending downward from a rack bar 62 slidable in a suitable guide portion formed in the slide or base 52. It is to be observed that the pins 53 pass through slots 63 and are screwed into the respective anchor members. Pivoted between the guides 25 is a segment 64 having an inwardly extending arm 65 carrying a roller 66 which lies beneath the counterweight 27.

Now considering the operation of this part of the mechanism, it will be seen that as soon as the shaft 16 rotates the disk 50 rotates therewith, and due to the action of the springs 55 on the pins 53, the anchor members are pulled into respective notches 51 and there held, the cams 60 acting upon the pins 61 to move the racks 62 inwardly and swing the arms 55 upwardly thus raising the rollers 66. When the weight descends it strikes these rollers and imparts movement to the arms 65 which forces the rack 62 outwardly, and releases the anchor lug 59 from its engaged notch so that the springs 23 may then restore the parts. Fixed on the shaft 16 below the spider 49 is an interrupted or segmental wheel 67, having grooved peripheral portions 68 centrally of which are secured the ends of chains 69 leading around guide pulleys 70 in the base 11, and over guide pulleys 71 at the upper ends of the guides 25, remaining ends of said chain being secured to lugs 72 on the weight 27. These chains are not fixed permanently to the center of the segment 68, but there is employed a sliding trip device movable around the peripheral portion 68 and including a strap 73, which fits over said peripheral portions and carries a pin 74 normally fitting in a notch in the center of the respective segment 68, the pin being held in the notch by means of a coil spring 75 mounted within the strap. The ends of the pin 74 project above and below the strap so as to engage the guide members 76 which are carried by arms 77 projecting from a

collar 78 revolubly mounted on the shaft 16. These arms also carry the worm racks 79 wherewith mesh worms 80 driven by a gear train, a portion of which is shown at 81 from 5 a shaft 82 controlled by hand wheel 83, and having a lug or jamb nut 84. By this means the trips 76 can be shifted to the right or left, and thus insures release of the pins 74 from the notches in the segment 68 sooner or 10 later than the normal release in accordance with the direction of rotation of the shaft 16, thus enabling the device to be set for different times of exposure of the stop signal to one street or another. In operation the 15 movement of a vehicle across a platform draws on one of the chains 21 thus moving arm 20 to one side or the other and thereby moving the segmental wheels 67. Since the straps 73 are, at the start of the operation 20 locked to the segments of the wheel 67 the chains 69 will lift the weight 27 and thus movement will continue until the ends of the pins 74 strike the trips 76 whereupon the straps will be released from the respective 25 segments and the weight 27 will start to fall since these straps can now move along the segments. Meanwhile the arm 20 will have been locked in position by the mechanism shown best in Figures 6 and 7. Thus 30 the semaphore will have been turned and remain turned until the weight, descending slowly because of the action of the dash pot, has engaged and released the locking mechanism whereupon the springs 23 act to re- 35 store the arm 20 and semaphore to normal position and, in so doing, move the segmental wheel 67 back to normal so that the straps may again lock on their segments ready for the next operation.

40 From the foregoing it will be seen that after a car crosses the platform, the semaphore will remain set for a period which may be determined accurately, and will then return to neutral, and that the period during 45 which the semaphore remains set may vary in accordance with the stop signal being displayed for one street or the other.

There has thus been provided a simple and efficient device of the kind described and for 50 the purpose specified.

It is obvious that minor changes may be made in the form and construction of the invention without departing from the material spirit thereof. It is not, therefore, 55 wished to confine the invention to the exact form herein shown and described, but it is desired to include all such as properly come within the scope claimed.

60 Having thus described the invention, what is claimed as new, is:

1. In a street crossing semaphore, a shaft carrying a signal device, means to operate said shaft from a remote station to set the signal, spring means tending to restore the signal to neutral position, a ratchet moving 65 with the signal, a pawl engaging the ratchet, trip means for releasing the pawl and in-

with the signal, a pawl engaging the ratchet, trip means for releasing the pawl and including a member actuated to move from normal position upon setting of the signal and movable independently of the signal movement to return to normal, and means to retard the return of said member to normal position. 70

2. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a member actuated to move from normal position upon setting of the signal and movable independently of the signal movement to return to normal, means to retard the return of said member to normal position, and a regulating device for the 80 retarding means. 85

3. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, and release means in the path of the grip for freeing the same from said element. 90 95 100

4. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, and adjusting means connected to said release means for regulating the position of said release means and connected thereto. 110 115 120

5. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and in- 125 130

cluding a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, and means connected to the trip releasing member to retard the return of said member to normal position.

6. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, adjusting means connected to said release means for regulating the position of said release means and connected thereto, and means connected to the trip releasing member to retard the return of said member to normal position.

7. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, means connected to the trip releasing member to retard the return of said member to normal position, and a regulating device for the retarding means.

8. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to

move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, adjusting means connected to said release means for regulating the position of said release means and connected thereto, means connected to the trip releasing member to retard the return of said member to normal position, and a regulating device for the retarding means.

9. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, a dash pot having a bleeder opening, and a piston moving in said dash pot and having connection with said trip releasing member to retard the movement thereof in one direction.

10. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, adjusting means for regulating the position of said release means, a dash pot having a bleeder opening, and a piston moving in said dash pot and having connection with said trip releasing member to retard the movement thereof in one direction.

11. In a street crossing semaphore, a shaft carrying a signal device, means to operate said shaft from a remote station to set the signal, spring means tending to restore the

- signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, a dash pot having a bleeder opening, a piston moving in said dash pot and having connection with said trip releasing member to retard the movement thereof in one direction, the connection, including a ratchet device permitting said member to move freely in the other direction independently of the piston, said ratchet device further permitting movement of the piston independently of the trip release member for restoring the piston to normal position.
12. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, adjusting means for regulating the position of said release means, a dash pot having a bleeder opening, a piston moving in said dash pot and having connection with said trip releasing member to retard the movement thereof in one direction, and a needle valve regulating the escape of air from said bleeder opening.
13. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, adjusting means for regulating the position of said release means, a dash pot having a bleeder opening, a piston moving in said dash pot and having connection with said trip releasing member to retard the movement thereof in one direction, the connection including a ratchet device permitting said member to move freely in the other direction independently of the piston, said ratchet device further permitting movement of the piston independently of the trip release member for restoring the piston to normal position.
14. In a street crossing semaphore, a shaft carrying a signal device, means to operate said shaft from a remote station to set the signal, spring means tending to restore the signal to neutral position, a ratchet moving with the signal, a pawl engaging the ratchet, trip means for releasing the pawl and including a trip releasing member actuated to move from normal position upon setting of the signal and movable independently of the signal movement to return to normal, an element moving with said signal, a grip operatively connected to said trip releasing member to move the same from normal position and releasably gripping the element, release means in the path of the grip for freeing the same from said element, adjusting means for regulating the position of said release means, a dash pot having a bleeder opening, a piston moving in said dash pot and having connection with said trip releasing member to retard the movement thereof in one direction, the connection including a ratchet device permitting said member to move freely in the other direction independently of the piston, said ratchet device further permitting movement of the piston independently of the trip release member for restoring the piston to normal position.

In testimony whereof I affix my signature.

ARTURO DURÁN.
